UNITED STATES PATENT OFFICE.

FRANCIS J. STOKES, OF PHILADELPHIA, PENNSYLVANIA.

AGITATOR-CONVEYER FOR DRIERS AND THE LIKE.

1,253,543.

Specification of Letters Patent. Patented Jan. 15, 1918.

Application filed June 3, 1916. Serial No. 101,600.

To all whom it may concern:

Be it known that I, FRANCIS J. STOKES, a citizen of the United States, residing at Philadelphia, in the county of Philadelphia and State of Pennsylvania, have invented a certain new and useful Agitator-Conveyer for Driers and the like, of which the following is a specification.

The principal object of the present invention is to reduce the power required to drive the agitator-conveyers of driers and the like without reducing their efficiency or effectiveness, and for the accomplishment of this object my invention, generally stated, comprises a construction and relative arrangement of the conveyer flights, by which the latter may not operate in opposition to each other upon the material upon which they are working, and in which one of the flights of unlike spiral direction is interrupted and the other is continuous at the crossing of the pitch lines of the flights, so that the material operated upon by the continuous flight may pass along the wall of the casing and freely through or past the space formed by the interrupted flight and thus reduce the power required to turn the agitator-conveyer.

The invention will be claimed at the end hereof but will be first described in connection with a type of drying chamber chosen from other like apparatus for illustration in the accompanying drawings forming part hereof and in which—

Figure 1, is an elevational view, partly in section, and

Fig. 2, is a transverse section taken on the line 2—2, of Fig. 1.

In the application of the invention selected for the sake of description, the outlet 1, of the casing 2, is at the center midway of its length, so that the parts of the agitator-conveyer on each side of the outlet are shown as relatively reversed but otherwise alike, and a description of one end will therefore suffice. The flight 3, is of spiral direction appropriate for conveying, while agitating, material in the direction of from the outlet 1, to one end of the casing. The flights 4, are of opposite and appropriate spiral direction for feeding, while agitating, material in the direction of from an end of the casing to the outlet 1. This description assumes that rotation of the shaft 5, which carries the blades or strips constituting the flight, is appropriate, for it is

obvious that the direction of feed of any spiral flight depends upon the direction of rotation of its shaft. One of these flights, in the present instance the flight 3, is continuous from an end of the casing to the outlet 1, and the other flight, is interrupted at the crossing of the pitch lines of the flights, so that the discontinuous flight, consists of sections, in the present instance three sections, two of which, marked 4, are spaced apart as at 6, and each section is relatively short in comparison with the flight 3. 7, are arms radiating from the shaft 5, and they carry the flights of the conveyer-agitator. 70 The arms which carry the discontinuous flights, are shown as longer than the arms which carry the continuous flight 3, so that the flights 4, are nearer to the casing wall than the flights 3. 75

In use the flights operate to convey material in the casing toward and away from the center and so agitate it, and when the outlet is open they serve to discharge the material from the casing. The spaces 6, in the discontinuous conveyer, or more accurately between the sections which make up that conveyer, occur where the conveyer 3, crosses the pitch line of the discontinuous conveyer 4, so that these spaces afford passages through which material driven by the conveyers, freely passes, and as the material acted upon is frequently viscous and heavy, especially at the beginning of the drying operation, this effects an economy in the power required to drive the machine. The sections of conveyer 4, nearest the end of the casing 2, and the outlet 1, are arranged in the same spiral line, and the intermediate section 4^a is arranged in a different but parallel spiral 95 line and opposite to the spaces 6, so as to bridge the space 6, between the two first mentioned sections and generally equalize the effect of the two spirals. Moreover the sections 4^a, scrape the spaces 6, and so when 100 the outlet is open the sections 4 and 4^a, discharge all the material through it. It may be said that although the flights 4 and 4^a, are in parallel spirals they appear to cross each other at the spaces 6, but that appearance is due to the fact that the spaces 6, and the flights 4^a, are shown diametrically opposite in respect to the casing, or perhaps more accurately, in respect to an imaginary cylinder inclosing the spiral flights. 105

What I claim is:

1. In apparatus of the type recited the

combination of a stationary normally closed casing, and revoluble agitator-conveyer flights of right and lefthand spiral direction adapted to coöperate with the wall of the casing and of which one is continuous and the other consists of sections spaced apart at the crossings of the pitch lines of the spirals, substantially as described.

2. In apparatus of the type recited the combination of a stationary normally closed

casing, and revoluble agitator-conveyer flights of right and lefthand spiral direction adapted to coöperate with the wall of the casing and of which one is continuous and the other comprises sections spaced apart at 15 the crossings of the pitch lines of the spirals and also other sections arranged on parallel spiral lines and opposite the spaces between the first mentioned sections.

FRANCIS J. STOKES.
